Primary Examiner—Cynthia E. Ramirez(74) *Attorney, Agent, or Firm*—Jacobson Holman PLLC(57) **CLAIM**

The ornamental design for a trash can receptacle, as shown and described.

DESCRIPTION

FIG. 1 is a top perspective view of a trash can receptacle showing a first embodiment of my new design;

FIG. 2 is a left side elevational view of the trash can receptacle of FIG. 1, the right side elevational view being a mirror image thereof;

FIG. 3 is a top plan view of the trash can receptacle of FIG. 1;

FIG. 4 is a bottom plan view of the trash can receptacle of FIG. 1;

FIG. 5 is a top perspective view of a trash can receptacle showing a second embodiment of my new design;

FIG. 6 is a left side elevational view of the trash can receptacle of FIG. 5, the right side elevational view being a mirror image thereof.

FIG. 7 is a top plan view of the trash can receptacle of FIG. 5; and,

FIG. 8 is a bottom plan view of the trash can receptacle of FIG. 5.
